UNITED STATES PATENT OFFICE.

EDWARD L. KUNZ, OF BUFFALO, NEW YORK, ASSIGNOR, BY MESNE ASSIGNMENTS, TO ONE HAND AUTO TOP CO., INC., OF BUFFALO, NEW YORK, A CORPORATION OF NEW YORK.

AUTOMATICALLY-OPERABLE TOP-FRAME.

1,334,381.

Specification of Letters Patent. Patented Mar. 23, 1920.

Application filed August 19, 1916. Serial No. 115,882.

To all whom it may concern:

Be it known that I, EDWARD L. KUNZ, a citizen of the United States, residing at Buffalo, in the county of Erie and State 5 of New York, have invented certain new and useful Improvements in Automatically-Operable Top-Frames; and I do hereby declare the following to be a full, clear, and exact description of my invention, such as 10 will enable others skilled in the art to which it appertains to make and use the same, reference being had to the accompanying drawings, and to figures and references marked thereon, which form part of this specification. 15

Like figures of reference refer to like parts.

This invention relates to top frames for either land or water conveyances, and particularly for vehicles of any of the standard lengths. It belongs to that class of collapsible frames, which are automatically operable by hand or motor power.

In providing a top frame for long cars 25 or motor boats, strength of frame and ease of operation, considering the length of frame and weight thereof, are important. Hence, one of the objects of my invention is to provide a light and strong frame, having a trussed and jointed structure, that 30 can be used on long as well as short conveyances.

Another object is to provide such operating and frame handling mechanism, which 35 will be capable of carrying the frame in any position between full open and folded, without impairing the strength of any of the parts of said mechanism.

A further object is to provide a collapsible 40 top frame which will operate within the garage, if desired, requiring no excessive head room from its operation.

I have also sought the usual objects of 45 cheapness, durability and strength, that will lend to the popularity of this invention, as an article of manufacture.

To fulfil the above objects I have provided 50 certain details of construction, included in a collapsible frame, having a trussed side structure, of a multiple lazy-tong construction, partly pivoted to upright arms, and partly pivoted to nuts in engagement with threaded shafts, journaled longitudinally in the arms, there being one shaft in each 55 arm, and the shafts being so connected

across the tops of the arms, that either shaft turns the opposite one. Cross yokes with flexible straps, are provided. I also provide mechanism connected with the arms for moving them angularly, which is connected and synchronized with the threaded shafts. To govern the travel of the uppermost parts and confine them to a desirable and practically low path, I provide a tripping mechanism that alters the linked motion of the lazy-tongs. 60 65

One embodiment of my invention is shown in the figures, and is hereinafter described in detail; the operation of the parts is explained, and what I claim is set forth. 70

In the drawings

Figure 1 is a side elevation of an auto body, having fitted thereto a top frame, embodying my invention.

Fig. 2 is a front section elevation of part 75 of the frame shown in Fig. 1, and particularly illustrates the side arms and the threaded shaft journaled longitudinally therein and connected by a cross shaft and flexible shafts. 80

Fig. 3 is a side elevation of the head of one of the arms, showing the relative pivoted positions of various links in the frame, connected therewith.

Fig. 4 is a top plan of the construction 85 shown in Fig. 3.

Fig. 5 is a sectional elevation showing the beveled gear construction, with shafts journaled in the end of one of the arms, including a crank handle, positioned for operation. 90

Fig. 6 is a front elevation of the construction shown in Fig. 5.

Fig. 7 is a horizontal section taken on the line X—X of Fig. 6, being one of the swinging arms, including the centrally located threaded shaft. 95

Fig. 8 is an elevation of one of the gear mechanisms, positioned within one side of the vehicle body, and shows one form thereof for governing the angular position of one of the swinging arms. 100

Fig. 9 is a sectional elevation of the construction shown in Fig. 8.

Fig. 10 is an elevation showing a different form of gearing to that shown in Fig. 8, for governing the angular position of one of the swinging arms. 105

Fig. 11 is a sectional elevation of the construction shown in Fig. 10. 110

Fig. 12 is a plan showing the construction of the end of the rear cross yoke of the top frame shown in Fig. 1, illustrating a spring connected therewith for throwing said yoke to have its plane coincide with the plane of the links, to which it is connected, as the said frame is folded.

Fig. 13 is a side elevation of mechanism similar to that shown in Fig. 1, but partially folded (or extended).

Fig. 14 is a side elevation of mechanism similar to that shown in Fig. 1, but in the full folded position.

In Fig. 1, 1 is the body of the vehicle, having a wind shield 2. Rotatably mounted upon a bearing, fixed in the body 1, is the gear casing 3, within which is journaled the stub shaft 4, having a square recess 5, for the reception of a crank. Projecting above the gear casing 3, and integral therewith, is the arm 6, having straight track portions, 7 and 8. Axially positioned within the arm 6, is journaled a threaded shaft 9, engaged by a nut 10. This nut 10, has projecting ears 11 and 12, to which are pivoted, respectively, the links 13 and 14, on the respective pins 15 and 16. Journaled upon the pins 15 and 16, are rollers 17 and 18, positioned to engage the respective track portions 7 and 8, to carry directly thereon any stress coming from the links 13 and 14, and thus relieve the shaft 9 of said stress. The arm 6, terminates in a flat head 19, to the upper portion of which are pivoted link 20, on the pin 21, and link 22 on the pin 23. Also pivoted to the head 19, is a slotted link 24, having the angular slot 25, through the outer end of which the pin 26 passes, in sliding engagement therewith. 27 is a bent link pivoted by the pin 28, to the link 22, and also pivoted by the pin 29, to the link 14. The short arm 30, of the link 27, has fixed thereto, an ear 31, upon which is pivoted a pawl 32, having a form and position adapted for engagement with the elbow 33, of the link 24, during the angular movement of the links. Pivoted by the pin 34, to the outer end of link 14, is a bent link 35, the shape of which is such as to conform to that of links 22 and 27, when the links are in folded position. The link 36 is pivoted by the pin 37, to the link 27; and the link 38 is pivoted by the pin 39, to the link 36. The link 40, is pivoted by the pin 41, to the link 35. Links 35 and 36 are pivoted by pin 35^a. Links 14, 36 and 40, are preferably made of two parallel members, spaced for balancing the construction and for the free angular movement of the other links, pivoted thereto.

Returning now to the head 19 of the arm 6; the link 13, in the normal open position of the top frame, is preferably horizontal, which necessitates pivoting the links 13 and 20 at varying distances, respectively, from the pins 15 and 21, and the angular move-

ment of these links during the operation of the top frame necessitates the positioning of the pin 42, within a slot 43, in the link 13. To the outer end of the link 13, on the pin 44, is pivoted the cross yoke 45, having a coil spring 46, adapted to throw yoke 45, to have its plane in line with the axis of the link 13, when the band portions 47 and 48 become limp, in the movement of the top frame. This construction of cross yoke 45, with its attachment to the link 13, is made for the purpose of having these members automatically adjustable to the requirements of the respective folding positions of the links. A similar set of swinging arm and links, with gear casing, etc., to that just described, is mounted on the opposite side of the vehicle, and the two sets are connected in the following way: The cross yoke, 45, is pivoted to a link similar to link 13. The swinging arm 6, and its duplicate, are fixed to a cross yoke 49, by screws 50 and 51. The link 14 and its duplicate, are pivotally connected to cross yoke 52, by the pins 53. Link 36 and its duplicate are connected to the cross yoke 54, by the pins 55. The outer ends of the links 40, are connected by the cross piece 56, to which is attached a securing device 57, adapted to secure the outer end of the top frame to the wind shield 2. The cross yokes, 45, 49, 52, and 54, and the cross piece 56, are connected by parallel bands 58, which are fixed at the point 59, to the rear of the body 1. A hanger 60, is provided as an outer support for the links in their folded position.

Referring to Fig. 2. 1 is the automobile body, and lines 61 and 62 represent the upholstery. 63 and 64 are gear boxes, containing similar sets of gear mechanism, one being right and the other left in their construction and action. 4 and 4¹, are recessed stub shafts for receiving the crank. 3 and 3¹, are gear casing, from which project the pivoted arms 6 and 6¹. 8 and 8¹, and the forward track portion of the arms 6 and 6¹, respectively. 9 is the left-hand threaded shaft. 9¹ is the right-hand threaded shaft. Threaded with shaft 9, is the nut 10, having the ear 12. Threaded with the shaft 9¹ is the nut 10¹, having the ear 12¹. The upper end of the arm 6, has a head 19. The upper end of the arm 6¹, has a head 19¹. The arm 6, has a curved tubular extension 65, in which is rotatably mounted a short piece of flexible shafting 66. Within a tubular curved extension 65¹, of the arm 6¹, is rotatably mounted a flexible shaft portion, similar to 66. The flexible shaft 66, is connected at the upper end of the threaded shaft 9, and the other end of the shaft 66, is connected with a horizontal shaft 67, which is also connected with the flexible shaft within the curved portion 65¹, which in turn is con-

nected to the shaft 9¹, so that when either shaft 9 or 9¹ is rotated, the other shaft is turned.

Referring to Fig. 3, on arm 6, is shown track portions 7 and 8, engaged by rollers 17 and 18 respectively, which are journaled upon pins 15 and 16 respectively, to which are connected the links 13 and 14. To the head 19, is screwed cross yoke 49, by the screws 50 and 51. The slotted link 24 is shown connected with the link 22 by a compression spring 24^a, which tends to keep the outer slotted end of the link 24, normally engaged with the pin 26, holding link 22 in trussed engagement with the head 19, until the elbow 33, of link 24, is forced upward, so that the pin 26, engages the long part of the slot 25, causing the unlocking of the link 22, from its trussed position, with respect to the head 19, and permitting the angular movement of the link 22, on its pivot pin 23.

In Fig. 4, the spacing of the parallel members of each of the links 13 and 14 is shown, as well as the central positioning of the respective links 20, 22, and 24. Rollers 17 and 18 are shown engaging the respective tracks 7 and 8.

Referring to Fig. 5. The arm 6 is shown fixed to the gear casing 3. Within the arm 6 is journaled shaft 9, to which is fixed the bevel gear 68. The recessed stub shaft 4, is fixed with the bevel gear 69, which meshes with the gear 68. Fixed to the gear 69 is a shaft 4^a, journaled in the tubular portion 3^a, of the gear casing 3. The outer surface of the tubular portion 3^a, is adapted for journaling with a suitable bearing in the body 1, of the automobile. Engaging the recess 40 within the stub shaft 4, is a crank 4^b.

Referring to Fig. 6. The outer part 3^b of the gear casing 3, is shown attached to the remaining part of the gear casing by screws 70 and 71.

Referring to Fig. 7. The central position of threaded shaft 9, with respect to the arm 6, is shown. The track portions 7 and 8 are also shown.

Referring to Figs. 8 and 9, the gear box 63 is shown fastened to the wall 1, of the automobile body. Also fastened to the said wall is plate 72, attached by bolts, 73 and 74. This plate 72 is an extension of a bearing 75, fixed in the wall of the said body 1, for the purpose of journaling the tubular portion 3^a, of the gear casing 3. The shaft 4^a extends within the gear box 63, and has fixed thereto, the gear 76. To a screw shaft, 77, which is fixed in the plate 72, is journaled the gear 77, which meshes with the gear 76. Fixed to the gear 77 is a smaller gear 78. The screw shaft 79, which is fixed in the plate 72, has journaled thereon a large gear 80, which meshes with the gear 78. Fixed 65 to the gear 80 and concentric therewith, is a

small gear 81, which meshes with the circular rack 82. The circular rack 82 is made part of the extension 3^a, of the gear casing 3, so as to rotate with the gear casing 3, and the arm 6.

Referring to Figs. 10 and 11, the tubular extension 3^a, of the gear casing 3, is shown journaled in the journal box 75, which is attached to the wall of the vehicle body 1. The gearing construction within the casing 3 is similar to that shown in Fig. 9. Fixed upon the wall of the vehicle body 1, is a circular rack 83. The plate 84 is integral with the inner end of the tubular portion 3^a of the gear casing 3, and revolves with it on the journal box 4^a. Fixed to the shaft 4^a is the gear 85. A plate 86, is provided and spaced from the plate 84, and connected therewith by the screws 87, 88, and 89, upon which are journaled the following gears: On screw 87 are journaled the two gears 90 and 91, the gear 90 meshing with the gear 85; and the gears 90 and 91, being fixed together. Journaled upon the screw 88, are the gears 92 and 93, which are fixed together, the gear 92 meshing with the gear 91. Journaled upon the screw 89 are the gears 94 and 95, which are fixed together, the gear 94 meshing with the gear 93, and the gear 95 meshing with the stationary rack 83.

Referring to Fig. 11, the relative angular positions of the arm 6 and the plates 84 and 86 with the rack 83 are shown.

Referring to Fig. 12, one end of the cross yoke 45 is shown, having a bracket 45^a integral therewith. The pin 44 is shown passing through the bracket 45^a, and the extension 45^b, of the cross yoke 45, and journals the link 13 with the yoke 45. In between the bracket 45^a and the extension 45^b, 105 is the spring 46, having one leg 13^a, thereof, bearing upon the link 13, and another leg 45^c, thereof, bearing upon the bracket 45^a. Projecting from the cross yoke 45, is the lug 45^d, which acts as a stop for the outer end of 110 the link 13, to limit its position to the plane of the cross yoke 45, to be normally in line with the axis of the link 13.

In operation, referring to Figs. 1 and 13, in Fig. 1, the top frame is in extended position, we will say, about to be folded. The top frame is released at the securing device 57, from the wind shield 2. The crank 4^b, shown in Figs. 5 and 6, is inserted in the recess 5 of the stub shaft 4, and as it is turned, 120 both the shafts 4^a and 9 are rotated, through the intermeshing of the gears 68 and 69.

Referring to Figs. 8 and 9, the resultant action of the turning of the shaft 4^a is to cause the rotation of the gear casing 3. The gear 76 rotates the gear 77, and the gear 78 rotates the gear 80, the gears 77 and 78 being fixed together. Gears 80 and 81, being fixed together, the gear 80 rotates, and having a permanent axis of rotation with re- 130

spect to the body 1, it causes the circular rack 82 to turn; which being fixed with the tubular extension 3^a, of the gear casing 3, causes an angular movement of the arm 6 attached thereto. By the meshing of the gear 68 with the gear 69, the rotation of the crank 4^b is communicated with the shaft 9, which turning within the nut 10, causes same (if rotated in the right direction) to travel downward, along the arm 6, carrying with it the links 13 and 14 (see Figs. 1 and 13) and continuing downward until some such position, of the nut 10, is reached, as is shown in Fig. 13; during which movement the link 27, is turned about the pin 28, as a fixed axis, and the outwardly extending links connected therewith, are caused to move through a comparatively low path. If now we continue to rotate the crank 4^b, in the same direction, causing further downward movement of the nut 10, the pawl 32, having come in contact with the elbow 33, of the slotted link 24, will cause the link 24 to rotate upward about its pivot point 24^b, until the pin 26 is moved downward to engage the long portion of the slot 25, and the further movement of the nut 10, brings into an angular action, the previously trussed link 22, permitting the folding together of the parts, as is shown in Fig. 14, until they rest upon the hook 60. During the travel of the nut 10, along the arm 6, the band portions 47 and 48 have become limp, and the spring 46, shown in Fig. 12, becomes free to throw the cross yoke 45 into a position having its plane in line with the axis of the link 13, and remains there during the further movement of the nut 10, drawing the links into the folded position of the frame shown in Fig. 14.

An alternate form of mechanism used for angularly positioning arm 6, is shown in Figs. 10 and 11, and operates in the following way: The plates 84 and 86, in which are positioned the screws 87, 88, and 89, acting as shafts for the gears, are fixed upon an extension 3^a, of the gear casing 3, and rotate therewith. The shaft 4^a being fixed to the gear 85, which meshes with the gear 90, rotates the same, as well as the gear 91, fixed thereto. The gear 91, meshing with the gear 92, rotates the same, as well as the gear 93, fixed thereto. Gear 93 rotates the gear 94, as well as the gear 95, fixed thereto. The gear 95 being in mesh with the fixed circular rack 83, forming a track upon which the gear 95 rolls, carries with it the plates 84 and 86, which rotate about the axis of the shaft 4^a, which rotation is communicated to the gear casing 3, fixed thereto, causing an angular movement of the arm 6. I preferably provide a complementary set of gear mechanism for the opposite arm 6¹, of the top frame.

I do not wish to be confined to the one

embodiment of my invention illustrated and above described, as changes may be made therein without departing from the spirit and scope of my invention, hence I claim:

1. In a top frame adapted for attachment to the body of a conveyance, a swinging arm journaled on the side of said body, means attached to the swinging arm adapted to govern its angular position with respect to the said body; a set of trussed links pivoted together, connected by a holding link pivoted to the outer end of said swinging arm; another of said links being pivoted to a longitudinally moving device upon said swinging arm, adapted to change the angular position of said links with respect to one another, to draw said links to said arm or to extend said links normally thereto; a slotted link pivoted on said arm near said holding link, and in sliding engagement with a pin on said holding link; a spring adapted to hold said holding link and said slotted link normally in trussed engagement; a tripping link of said set of links pivoted to the outer end of said holding link; a pawl pivoted upon said tripping link, and adapted by its position to engage said slotted link to release the same from trussed engagement with said holding link to permit the angular movement of said holding link with respect to said swinging arm and with respect to said engaged slotted link; and means for operating said top frame.

2. In a top frame, adapted for attachment to the body of a conveyance and comprising a swinging arm journaled on the side of said body, means attached to said arm adapted to govern its angular position with respect to said body, sliding means adapted for longitudinal reciprocation on said arm, and a set of trussed links pivoted together and pivoted to said arm and said sliding means, said links being opened and closed by the reciprocation of said sliding means; a device adapted to change the angular travel of said links, to cause the same to travel in a low path, said device comprising a holding link pivoted to said arm and to said set of trussed links, a sliding link pivoted to said arm and in sliding engagement with said holding link, said sliding and said holding links being spring pressed for holding said links in a trussed position, and means upon said set of links adapted to release the trussed relation of said holding and said sliding links, to permit of a sliding engagement of the same.

3. In a top frame adapted for attachment to the body of a vehicle, a swinging arm pivoted on said body, means engaging said arm for longitudinal movement thereon, a device for operating said means, an extensible cover-holding member in pivotal engagement with said means and said arm, and an element engaging said member and said arm

adapted to transfer any pressure from said member direct to said arm, to relieve said means of pressure coming from said member.

4. In a top frame for journaled attachment with the body of a vehicle, a swinging arm journaled for oscillation on said body, reciprocating means engaging said arm, a device for operating said reciprocating means, an extensible cover-holding member 10 in operative engagement with said reciprocating means and said arm, holding means connected with said arm adapted to govern and hold its angular position with respect to said body, said holding means including 15 a segmental rack and a train of gears, one of said gears meshing directly with said rack, another of said gears having its axis coincident with the axis of oscillation of said arm and adapted to revolve faster than the 20 gear meshing directly with said rack, transmission mechanism connecting said device with the said train of gears and means for operating said frame.

5. In a top frame adapted for journaled attachment to the body of the vehicle to support a cover to said vehicle, a swinging arm journaled for oscillation on said body, supporting means operable on said arm for supporting said cover, means connected with 25 said swinging arm adapted to govern and hold its angular position with respect to said body, said means including a segmental rack fixed upon said body and positioned concentrically with respect to the point of 30 oscillation of said swinging arm, a gear frame fixed on said arm and extending toward said rack, a train of gears journaled in said gear frame, one of said gears meshing with said rack, another of said gears 35 having an axis common with the axis of oscillation of said arm, said train of gears being arranged to have the gear meshing with the rack revolve slower than the gear having its axis common with the axis of 40 oscillation of said arm, and means for operating said gears.

6. In a top frame attached to a vehicle body, the combination with a pair of arms pivoted on said body, of a yoke rigidly connecting said arms, a long threaded shaft journaled longitudinally with each arm, power-transmission means connecting said shafts, a nut threaded with each shaft and 45 slidingly engaging the arm on which the shaft is journaled, a collapsible frame pivoted to each nut and to that arm with which said nut directly operates, a pressure relieving device connected with each nut contacting said arm with which said nut operates 50 adapted to relieve said shaft of stress coming from said frame, an element for turning each of said shafts, a device adapted to

change the angular position of each arm with respect to said body, means connected with each arm operatively connecting the 65 element and the device of each arm with which said device operates, whereby each of said shafts are rotated during the angular movement of said arms.

7. In a top frame adapted to be attached 70 to the body of a vehicle, a swinging arm pivoted in said body, means engaging said arm for longitudinal movement thereon, a device for operating said means, a set of extensible cover-holding members in operative engagement of said means and said arms, bracing means connecting said arms with said members, means for holding said bracing means in trussed relation with said members and said arms and other means 75 for automatically breaking the said trussed relation, during a closing movement of the said top.

8. In a top frame adapted for attachment to the body of a vehicle, a swinging arm 80 pivoted to said body, means engaging said arm for longitudinal movement thereon, a supporting member in pivotal engagement with said means and said arm adapted to hold a cover 85 thereon, said member including a terminal link pivoted to said arm, an element fixed upon said terminal link spaced from the pivot point of said terminal link with said arm, a second link pivoted to said terminal 90 link, a third link pivoted to said means and to said second link, a guiding member pivoted to said arm, said guiding member having a bent guide thereon in sliding engagement with said element, means for normally 95 holding said guiding member and said terminal link in trussed relation with respect to said arm, and other means on said second link adapted to engage said guiding member during an angular change of said 100 second link with said terminal link, to break the trussed relation of said terminal link and said guiding member with said arm, 105 whereby said terminal link is permitted to turn about its pivot point with said arm, during an angular movement of said links, the trussed relation of said terminal link and said guiding member with said arm affording a pivotal relation whereby said second link turns about a pivot point fixed and 110 spaced with relation to said arm, to cause said member to sweep through a comparatively low path with respect to said body, in the forward part of its cycle of motion.

EDWARD L. KUNZ.
